UNITED STATES PATENT OFFICE.

CHARLES COLLER, OF HANNIBAL, MISSOURI, ASSIGNOR OF TWO-THIRDS
TO WILLIARD T. BLOCK, OF SAME PLACE.

LID FOR CAR-AXLE BOXES.

SPECIFICATION forming part of Letters Patent No. 268,625, dated December 5, 1882.

Application filed May 16, 1882. (No model.)

To all whom it may concern:

Be it known that I, CHARLES COLLER, of Hannibal, in the county of Marion and State of Missouri, have invented a certain new and useful Improvement in Lids for Car-Journal Boxes, of which the following is a full, clear, and exact description, reference being had to the accompanying drawings, forming a part of this specification.

10 My invention relates to a non-detachable lid, which, when opened, will remain in that position without attention while the oiling is being done, and if negligently left open will automatically close by the jolting of the moving car.

15 My invention consists in forming a groove in the back of the lid, which receives the end of a strip of metal secured to the top of the box, and also in forming notches in the lower 20 end of the lid which holds the lid in its open position, by allowing its upper end to be thrown forward, as shown in the drawings, in which—

Figure 1 is a horizontal section through the center of the box, showing the end of a car- 25 axle. Fig. 2 is an end view, showing the lid closed. Fig. 3 is an edge view of the lid. Fig. 4 is a detail side view of the box, part in section, the lid being shown in section and in its 30 opened position; and Fig. 5 is a front view of the lid.

A represents the box, and B the lid for closing the oil-opening.

C is a strip or plate of metal secured by screws, or otherwise, to the top of the box.

35 D is a groove in the back of the lid, which receives the outer end of the strip C. The groove does not extend quite the whole length of the lid, as shown, so that the plate prevents the removal of the lid from the box, either up-

ward or downward, and consequently avoids 40 any danger of loss. The lid works in grooves of flanges E E cast upon the box each side of the oil-opening.

F is a projecting lip on the upper end of the lid, to be used as a hand-hold in raising the 45 lid.

G G are V-shaped notches in the face of the lower end of the lid. When the lid is opened and its upper end thrown forward these notches receive the upper ends of the flanges E, (see 50 Fig. 4,) and thus the lid is held in its opened position while the oiling is being done. Should the lid be left open the jolting of the car, when it starts, will cause the inclined faces of the notches to slip off the flanges, which will allow 55 the lid to gravitate into its closed position.

I do not confine myself to the exact shape of the notches described and shown, for other shapes might answer the purpose equally as well.

If it is desired to put a new lid on the box it is only necessary to remove the strip C, which will allow the old one to be taken off and a new one substituted.

What I claim, and desire to secure by Letters Patent, is—

In a car-journal box, the lid working in grooves of flanges cast upon the box and provided with notches at its lower end for engaging with the tops of the flanges, and a groove 70 in its back for receiving the end of a strip or plate secured to the box, all substantially as and for the purpose set forth.

CHAS. COLLER.
